US00D912235S

(12) **United States Design Patent** (10) **Patent No.:** **US D912,235 S**
(45) **Date of Patent:** **** Mar. 2, 2021**

(54) **AIR PURIFIER**

- (71) Applicant: **Coway Co., Ltd.**, Choongcheongnam-do (KR)
- (72) Inventors: **Sul Ki Lee**, Seoul (KR); **Mikyung Kim**, Seoul (KR); **Jong Ho Choi**, Seoul (KR); **Ga Hee Kim**, Seoul (KR)
- (73) Assignee: **Coway Co., Ltd.**, Choongcheongnam-do (KR)
- (**) Term: **15 Years**
- (21) Appl. No.: **29/697,057**
- (22) Filed: **Jul. 3, 2019**

(30) **Foreign Application Priority Data**

Jan. 7, 2019 (KR) 30-2019-0000819

- (51) LOC (13) Cl. **23-04**
- (52) U.S. Cl. **USPC D23/364**

(57) **CLAIM**

The ornamental design for an air purifier, as shown and described.

DESCRIPTION

FIG. 1 illustrates a front perspective view of the air purifier showing our new design;

FIG. 2 illustrates a front elevational view thereof;

FIG. 3 illustrates a rear elevational view thereof;

FIG. 4 illustrates a left side elevational view thereof;

FIG. 5 illustrates a right side elevational view thereof;

FIG. 6 illustrates a top plan view thereof; and

FIG. 7 illustrates a bottom plan view thereof.

FIG. 8 illustrates a front perspective view of the air purifier showing our new design;

FIG. 9 illustrates a front elevational view thereof;

FIG. 10 illustrates a rear elevational view thereof;

FIG. 11 illustrates a left side elevational view thereof;

FIG. 12 illustrates a right side elevational view thereof;

FIG. 13 illustrates a top plan view thereof; and,

FIG. 14 illustrates a bottom plan view thereof.

The broken lines shown in the figures are for the purpose of illustrating portions of the air purifier that form no part of the claimed design.

1 Claim, 14 Drawing Sheets
